(57) **CLAIM**

the ornamental design for a fitness weight destabilizer, as shown and described.

DESCRIPTION

FIG. 1 is a perspective view;

FIG. 2 is a right end view thereof;

FIG. 3 is a front view thereof, the rear view being a mirror image thereof; and,

FIG. 4 is a top view thereof, the bottom view being a mirror image thereof.

The broken line showing of portions of the fitness weight destabilizer depicts environment and forms no part of the claim. The claimed design is shown with a symbolic break in its length. The appearance of any portion of the article between the break lines forms no part of the claimed design. The design is for a fitness weight destabilizer, which is used to destabilize weights and weights sets, such as olympic bar weights, bar bell weights, dumbbell weights, and the like, during exercise.
